UNITED STATES PATENT OFFICE.

EDWARD C. NEWTON, OF LOS ANGELES, CALIFORNIA.

SAFETY TIMER GOVERNOR.

Application filed May 2, 1923. Serial No. 636,051.

My invention relates to a governor mechanism which is especially applicable for use in automatically advancing or retarding the timing of the ignition spark in internal combustion engine operations.

An object of my invention is to provide a governor mechanism embodying instrumentalities adapted, on being rotated, to move under the action of centrifugal force, 10 said governor mechanism being so constructed and arranged that when the speed of rotation reaches a predetermined rate the centrifugal force will be diminished and resistance to centrifugal force augmented relative 15 to increase in the speed of rotation, whereby a very sensitive action will be effected at both high and low speeds.

An object of my invention is to provide a governor mechanism with speed responsive 20 elements which operate under the action of centrifugal force to produce a normal governing action at a normal speed of rotation, and to produce a graded governing action, at and beyond a predetermined speed, proportional with the speed.

With the foregoing objects in view, together with such other objects and advantages as may subsequently appear, my invention resides in the parts and in the combination, construction and arrangement of parts hereinafter described and claimed.

The invention is illustrated in the accompanying drawings, in which—

Figure 1 is a plan view of the rotary element showing the operating parts thereon in normal position.

Figure 2 is a similar view with the operating parts in a partly advanced position.

Figure 3 is a similar view with the operating parts in their maximum advanced position.

Figure 4 is a view in cross section partly in elevation, showing the device as assembled.

Fig. 5 is a perspective view of the supporting element for the centrifugally actuated parts.

More specifically, 14 indicates a timer shaft which is adapted to be rotated in the usual manner from the crank shaft on an internal combustion engine.

In carrying out my invention I employ a centrifugal governor for opening and closing the ignition circuit at various moments relative to the position of the engine piston

and to the engine speed, which governor is here shown as embodying a rotary element 24 fixed on the timer shaft 14. The rotary element includes a sleeve 25 which is rigidly secured to the timer shaft in any desired 60 manner. Formed on the sleeve is a bracket 26 on which is mounted a weighted arm 27 pivoted at 28 on the bracket at a point eccentric to the axis of rotation of the rotary element, which arm is adapted to be moved outwardly under the action of centrifugal force.

A second bracket 29 is formed on the sleeve 25 and pivoted at 30 thereon is a weighted lever 31, which is adapted to swing 70 outwardly under the action of centrifugal force on rotation of the rotary arm. The weighted lever 31 is designed to have limited outward movement, for which purpose it is formed with a shoulder 32 which is 75 adapted to abut against the bracket 29 when the lever is in its outermost position, as shown in Figures 2 and 3, which shoulder is normally spaced from the bracket 29 as shown in Figure 1. A spring 33 connecting 80 with the bracket 29 engages the inner end portion of the lever as indicated at 34 and acts to yieldably oppose movement of the lever under the action of centrifugal force and serves to restore the lever to normal. 85

A second spring 35 extends between the outer end of the weighted arm 27 and the inner end portion of the weighted lever 31 which spring yieldably opposes outward movement of the weighted arm under the 90 action of centrifugal force and also acts to restore the arm to its normal innermost position. The outer end of the arm 27 is formed with an inclined face 36 and the inner end portion of the weighted lever 31 is formed with a projection 37 which normally bears against the inclined face 36 adjacent the upper portion thereof in such fashion that the movement of the weighted lever under the action of centrifugal force 95 will cause the projection 37 to move downwardly on the inclined plane 36 and thereby exert a pressure on the outer end of the arm 27 tending to rock the latter outwardly.

It will now be seen that on rotation of 100 the rotary element in the direction of the arrow A in Figure 1, the weighted arm 27 and weighted lever 31 will be caused to rock outwardly in opposite directions under the action of centrifugal force and that by rea- 105 110

son of the leverage effected by the weighted lever on the arm 27, together with the action of centrifugal force on the arm 27, the initial outward movement of the arm 27 will be accelerated until the weighted lever is thrown out of operative relation to the weighted arm by moving against the stop afforded by the bracket 29, as shown in Figure 2. The weighted arm is designed to have a continued outward movement under action of centrifugal force after the action of the weighted lever thereon has terminated; the weighted arm then moving outwardly under the action of centrifugal force in opposition to the spring 35 which movement is limited by a stop 38 formed on the bracket 36.

By this construction the arm 27 and lever 31 constituting the weighted elements of the centrifugal governor will each swing outwardly under the action of centrifugal force at low speed with their outward movement progressing in direct ratio to the increase in speed of rotation and the consequent increase in centrifugal force, until the speed of rotation and the resultant centrifugal force is such as to cause the lever 31 to come to rest, whereupon the action of the lever 31 in assisting outward movement of the arm 27 through the medium of the projection 37 on the lever riding over the inclined face 36 on the arm, will be terminated. The force exerted by the action of centrifugal force on the lever 31 being thus arrested when the speed of rotation reaches a predetermined point there will be a diminution of centrifugal force acting on the arm 27 when the speed of rotation reaches a predetermined point and there will be an increased resistance to the movement of the arm 27 under the action of centrifugal force on further increase in speed above the predetermined point by reason of the action of the spring 35 on the arm 27. It accordingly follows that the arm 27 will initially move outwardly in direct proportion to increase in speed of rotation up to a predetermined point at a constant ratio and thereafter will move at a lesser ratio at increasing speeds above the predetermined rate of speed.

Mounted on the outer portion of the weighted arm 27 is a contact member 39, here shown in the form of a wiper contact member, arranged to traverse a series of contact plates 40 carried on the inner face of the end wall of a shell or housing 41 extending over and encircling the rotary element.

It will be noted by referring to Figures 1, 2 and 3 that the wiper contact member 39 will be caused, on swinging movement of the arm 27, to move outwardly and inwardly relative to the axis of rotation of the rotary element so that it will traverse various circular paths of travel within the range of move-

ment of the outer portion of the weighted arm.

By reason of the wiper contact member being carried on a pivoted arm it will also be caused to move on an arc and to be advanced or retracted along the lines of its circular paths of travel and relative to a plane extending through the axis of rotation of the rotary element.

The wiper is thus caused to advance relative to its forward movement as the speed of the rotary element increases, and is caused to retract relative to its forward movement as the speed of the rotary element decreases.

It follows that as the wiper is advanced and retracted under the action of varying speeds, the movement of its meeting with the contact plates and the consequent closing of the circuit will vary, thus advancing or retarding the moment of sparking at the spark plug and accordingly varying the moment of ignition of the explosive charge in the engine cylinder relative to the position of the engine piston, as will be more fully explained hereinafter.

It will be understood that fluctuations in engine speed in the range from low to high speed will effect variations in the advance and retrograde movements of the wiper relative to its circular paths of travel within the range of movement of the arm carrying the wiper; the wiper advancing as the engine speed increases and retrograding as the engine speed diminishes, so that the sparking moment will be automatically advanced or retarded in exact accordance with variations in engine speed.

While I have herein described a specific embodiment of my invention and the particular application thereof, I do not limit myself to the exact details of construction and arrangement shown, but may employ such changes and modifications as come within the scope of the appended claims, it being obvious that, in adapting the device to meet varying conditions within the range of advance and retardation of the sparking moment desired, the degrees of movement of the wiper will be varied to meet the requirements.

I claim—

1. In a device of the character described, a rotary element, a weighted arm, a weighted lever, said arm and lever being pivoted on said element and operable to advance collectively under the action of centrifugal force up to a predetermined speed of rotation of said element, a yieldable connection between said arm and lever, an inclined plane on said arm, a projection on said lever operable on said inclined plane to advance said arm relatively to said lever in opposition to said yieldable connection, and means whereby said arm will be caused to advance independent of said lever.

2. In a device of the character described, a rotary element, an arm pivoted on said element, a lever pivoted on said element, said arm and lever being arranged to swing outwardly in opposite directions under the action of centrifugal force, means for yieldably opposing outward movement of said

arm and lever, means for limiting outward movement of the arm, and means for limiting outward movement of said lever; said last 10 named means being arranged to arrest outward movement of the lever before outward movement of said arm is arrested.

EDWARD C. NEWTON.
